UNITED STATES PATENT OFFICE.

CHARLES J. MOSES, OF BOGOTA, NEW JERSEY.

BOMB.

1,294,937.

Specification of Letters Patent. Patented Feb. 18, 1919.

Application filed January 9, 1918. Serial No. 210,992.

To all whom it may concern:

Be it known that I, CHARLES J. MOSES, a citizen of the United States of America, residing at Bogota, in the county of Bergen 5 and State of New Jersey, have invented new and useful Improvements in Bombs, of which the following is a specification.

The invention relates to improvements in bomb construction.

10 Its principal object is to provide a device of this character which may be dropped from great heights and assured of explosion at the time of impact with the earth.

15 A second object is to provide a device to be exploded by a percussion cap, the latter being set off by the impact of a piston member which operates against the retarding effect of an air-cushion.

20 A third object constitutes the provision of means attached to the free end of the piston whereby the bomb, when dropped, will be assured of impact with the earth on this means.

25 A fourth object is to make this means which is attached to the end of the piston of such diameter that it will not penetrate the earth at the time of impacting with the latter.

30 Other and further objects will appear as the device is set forth in detail in the description which follows.

In illustrating the invention, it is shown in but one embodiment to which, however, it is not to be restricted. An actual reduction 35 to practice may suggest certain desirable changes or alterations and these the right is claimed to make, in so far as they may be compatible with the spirit of the subjoined claim.

40 In the accompanying drawings:

Figure 1 is a perspective view of the invention.

Fig. 2 is the longitudinal sectional view.

Fig. 3 is the transverse sectional view.

45 Referring to the drawings, 1 is a cylinder which may be made of any suitable material but which is preferably made of metal. One end of this cylinder is open but the other end which is the bottom end is closed 50 and is indicated by the numeral 2. Approximately at its longitudinal center, a disk 3 is attached on the interior of the cylinder, being held in place by rivets or headed pins 4 which pass through the cylindrical wall of the cylinder at uniformly spaced 55 points thereon and enter the circular edge

of the disk 3. This disk 3 carries at its center a percussion cap 5 which is affixed therein in any suitable manner and which is adapted to be contacted with on its bottom 60 end.

The open end of the cylinder 1 is closed by a detachable cap 6 having an internally threaded flange, so that it may be screwed onto the open end of the cylinder 1 which is 65 provided with exterior threads at its top. At its center the cap 6 has affixed to it, by any suitable means of attachment, the fan-tail thumbpiece 8 by means of which the cap 6 is attached to or detached from the 70 cylinder 1.

The interior space of the cylinder, comprehended between the disk 3 and the cap 6, is designed as a compartment for explosive material, such as dynamite, trinitrotoluol, 75 or the like. The percussion cap 5 contacts, at its upper end, with this explosive material, and is designed to ignite the latter when set off by means yet to be described.

The bottom end 2 of the cylinder is provided with a central bore through which the piston rod 9 slidably passes, this rod receiving on its upper end, by threaded engagement in the center thereof, the piston 10. Both the piston 10 and the closed end 2 of 80 the cylinder are provided with series of apertures or openings spaced uniformly in circles concentric with the piston rods, the piston having the apertures 11 and the bottom 2 by the apertures 12. 90

At the lower or free end of the piston rod 9, a disk 13 is attached, the rod having its extreme end 14 reduced in diameter and provided with suitable threads by means of which engagement is effected with the disk 95 13. This reduction of the diameter in the end 14 results in the formation of a shoulder on the rod 9 and the disk 13 abuts this shoulder when secured in position on the rod.

The disk 13 is designed to be of such a 100 diameter as to preclude its entering the earth when the bomb is dropped from great heights and it is also to be of such weight that the center of gravity of the device as a whole will be in the vicinity of this disk. 105 With this arrangement the bomb is assured of hitting the ground disk foremost.

The holes 11 and 12 in the piston 10 and closed end 2 of the cylinder respectively are provided for the purpose of allowing the air 110 contained in the bottom portion of the cylinder to be ejected quickly when the pis-

ton 10 is moved in the cylinder. These holes are not such diameter, however, as to totally remove all evidences of an air-cushion above the cylinder at the time the bomb is dropped on the ground. There is intended to be a certain amount of air compressed above the piston, so that some resiliency may be had in the device at the time that it hits the ground, the air contained in the cylinder issuing through the apertures 11 and 12 at the proper rate to permit the piston to move toward the disk 3 with sufficient force to set off the percussion cap 5 by impact therewith.

When the device is in storage this arrangement for an air-cushion prevents the device from being accidentally set off, since the piston is not permitted to be forced against the percussion cap with sufficient impact to set off the latter.

The arrangement for the air-cushion also definitely establishes the force necessary to be imparted to the piston to set off the device, and therefore, makes it necessary that the bomb be dropped from a certain definite height in order to explode. This height can be predetermined by making the apertures 11 and 12 of the proper diameter to provide a very slight air-cushion or to form a very considerable one.

As a further precaution against accidental discharge in storage, a cotter pin 15 is provided which is designed to be removably inserted transversely through the piston rod 9. This pin by contact with the bottom of

the casing 1 prevents the end of the piston coming in contact with the cap 5. The pin 15 is intended to be withdrawn from the piston rod prior to the dropping of the bomb.

The dove-tailed fan piece before referred to is intended to aid in keeping the bomb in an upright position when it is falling.

The invention having been described, what is claimed as new and useful is:

In a bomb, a cylinder having a removable closure member at one end and apertured at the other end, a disk interior to the cylinder and permanently attached thereto at the longitudinal center of the latter, a percussion cap carried by said disk, a piston interior to the cylinder and movable from said apertured end to the said disk, a piston rod connected with the piston and passing slidably through the apertured end of the cylinder, and a disk of sufficient weight to lower the center of gravity of the device so that it will remain upright when falling, this disk being connected to that end of the piston rod exterior to the cylinder, the piston being provided with a plurality of apertures, whereby when the device is dropped, an air-cushion is formed between the piston and the first said disk to provide for a definite impact to be imparted to the percussion cap.

In testimony whereof I affix my signature.

CHARLES J. MOSES.
